UNITED STATES PATENT OFFICE.

CHARLES C. WILLIAMS, OF BOGATA, TEXAS, ASSIGNOR, BY DIRECT AND MESNE ASSIGNMENTS, TO THE WILLIAMS RAIL JOINT AND CHAIR CO., OF DEPOT, TEXAS, A CORPORATION OF DELAWARE.

RAIL-JOINT CHAIR.

1,099,628.

Specification of Letters Patent.

Patented June 9, 1914.

Application filed March 4, 1914. Serial No. 822,429.

To all whom it may concern:

- Be it known that I, CHARLES C. WILLIAMS, a citizen of the United States, residing at Bogata, in the county of Red River and State of Texas, have invented certain new and useful Improvements in Rail-Joint Chairs, of which the following is a specification, reference being had to the accompanying drawings.
- 10 This invention relates to new and useful improvements in rail joints and more particularly to a joint chair, the main object of the invention being to provide a simple and efficient joint chair adapted to be readily applied to the meeting ends of the rails and capable of securely connecting and clamping the same in position and holding them against any lateral or longitudinal movement.
- 20 Another object of the present invention is the provision of a rail joint chair of the above character which will possess advantages in points of efficiency and durability, is inexpensive to manufacture and, at the same time is simple in construction and operation.

With these and other objects in view, the invention consists in the novel features of construction, combination and arrangement 30 of parts as will be hereinafter referred to and more particularly pointed out in the specification and claims.

In the accompanying drawing forming a part of this application, Figure 1 is a detail 35 perspective view of a rail joint chair constructed in accordance with my invention; and Fig. 2 is a transverse sectional view of the same.

Referring more particularly to the drawing, 40 1 and 2 indicate the meeting ends of two rails which are suitably connected together and retained against lateral or longitudinal movement by the use of my improved joint chair.

45 My improved joint chair, which is herein indicated by the numeral 3, includes a body which forms the base 4 and one of the retaining flanges 5 of the joint chair. It will be noted that the base member 4 and the retaining flange 5, which extends up over one 50 of the longitudinal sides of the base of the rail, are integrally formed and are provided at the junction thereof with the recesses 6, adapted to receive the heads of the securing

spikes 7, which are driven into the tie and 55 retain the rails against lateral movement. Extending upwardly, vertically from the retaining flange, is one of the web engaging flanges 8, which is provided with a plurality of spaced openings adapted to receive the 60 securing bolts 9. The web engaging flange 8, together with the retaining flange 5, constitutes one of the fish plates, which retain the rail joint in position. The other fish plate, indicated by the numeral 10, includes 65 the vertical portion 11 adapted to engage the web portion of the rail ends and the inclined flange 12, which is arranged over the base flange of the rail, in a manner similar to the inclined portion of the retaining flange 70 5. The lower longitudinal edge of the inclined portion 12, is cut-away at each end, as indicated at 13 and formed upon opposite sides of the center of the longitudinal edge are outwardly projecting tongues which are 75 bent upon themselves to form sleeves 14.

The longitudinal edge of the base member 4 is provided at each end and at the central portion thereof, with tongues which are bent upon themselves to form sleeves 15, 80 which are adapted to be arranged in alignment with the sleeves 14 on the fish plate 10 and are adapted to receive the pivot pin 16, thus forming a hinged connection between the fish plate 10 and the body of the chair. 85 It will be noted that upon opposite sides of the center sleeve 16', the material which extends outwardly between the sleeves, forms suitable tongues 17, having notches 18 formed therein adapted to receive the 90 heated ends of the securing spikes 7' and thus retain this side of the joint chair in its operative position.

In order to more securely retain the fish plates in engagement with the web portions 95 of the rails, the bolts 9 are passed through the vertical web engaging members 8 and 11 and through the meeting ends of the rails and are provided with nuts 19 which are engaged with the threaded ends of the bolts 100 and securely tightened to retain the fish plates in their operative positions.

It will be apparent from the above description, taken in connection with the accompanying drawing, that I have provided 105 a simple and durable joint whereby, by the removal of the bolts 9, the fish plate 10 may be swung outwardly, so that the ends of the

rails may be easily removed from the chair. It will also be apparent that in placing the rail ends in position, they are first arranged upon the base 4 and engaged beneath the retaining flange 5, the fish plate 10 being swung back out of position and adapted to be readily arranged in position after the rail ends have been arranged in alinement within the chair. It will also be apparent 10 that my improved joint chair is extremely simple in construction and can be manufactured at a comparatively low cost.

While I have shown and described the preferred form of my invention, it will be 15 obvious that various changes in the details of construction and in the proportions may be resorted to for successfully carrying my invention into practice, without sacrificing any of the novel features or departing from 20 the scope of the appended claims.

Having thus described this invention, what I claim is:—

1. A device of the class described including a base plate having an angular fish plate formed integral therewith, the longitudinal edge of said base plate being cut-away to form tongues bent upon themselves to provide sleeves, a second angular fish plate having its lower inclined edge pro-

vided with outwardly projecting tongues 30 bent upon themselves to form sleeves, the material arranged between the sleeves on the base plate being adapted to be extended outwardly beneath the sleeves on the second fish plate and provided with central 35 notches, as and for the purpose set forth.

2. A device of the class described including a base plate having an angular fish plate formed integral therewith, sleeves formed on the longitudinal edge of the base plate 40 opposite the fish plate, a second angular fish plate, sleeves formed upon the lower edge of the second fish plate and adapted to be arranged in alinement with the sleeves on the base plate, a pivot pin arranged within 45 said sleeves to pivotally connect the second fish plate with the base, and outwardly projecting flanges formed on the base and extending beneath the sleeves on the second fish plate and said flanges being provided 50 with central notches, as and for the purpose set forth.

In testimony whereof I hereunto affix my signature in the presence of two witnesses.

CHARLES C. WILLIAMS.
